UNITED STATES PATENT OFFICE

JESSE A. BLANN, OF SYRACUSE, NEW YORK

TOILET ROLL LABELING MACHINE

Application filed April 4, 1930. Serial No. 441,548.

This invention relates to a machine for labeling toilet paper rolls after the latter has been cut into strips of the required widths and wound upon a suitable arbor or mandrel 5 in co-axial relation end to end.

That is, the paper is usually delivered from the paper-making machine in relatively wide sheets and during such delivery is cut into strips of the desired length for the rolls and 10 perforated at regular intervals, immediately following which the perforated strips of predetermined lengths are wound upon the arbor thereby forming a multiplicity of co-axial rolls upon each arbor or mandrel.

15 The main object of the present invention is to provide simple and efficient means for automatically and expeditiously labeling the rolls as supplied to the machine upon the mandrel. In other words I have sought to 20 take the mandrels with the multiplicity of rolls thereon directly from the paper making machine and pass them through the labeling machine in such manner that all of the rolls 25 on each mandrel will be simultaneously labeled.

One of the specific objects is to provide a power driven mandrel carrier with a plurality of bearings for the mandrels arranged 30 at spaced intervals throughout its length so that as soon as the rolls on one mandrel have been labeled the bearings for another mandrel with the unlabeled rolls thereon will be 35 in position to receive that mandrel for repeating the labeling operation upon its rolls.

Another specific object is to provide means 40 actuated by the bearings after the rolls thereon have been labeled for automatically stopping the machine to permit unloading of the labeled rolls and reloading of the unlabeled rolls from and upon the conveyor.

Another specific object is to provide means 45 for automatically applying adhesive substance to the opposite ends of each label without interrupting the continued movement of the mandrels with the rolls thereon along the label support whereby the rolls on the mandrel may automatically contact with the adhesive on one end of the label and thereby wrap the label around the rolls as they are 50 rolled along and upon said label so that the

adhesive on the other end of the label will be brought into overlapping contact with the first named end of said label for sealing the same and thus complete the labeling operation for the rolls on each mandrel without 55 interrupting the operation of the machine.

A further object is to provide means whereby the label holder will be intermittently and automatically fed toward the path of movement of the loaded mandrels a distance 60 corresponding approximately to the thickness of the label immediately following each labeling operation.

Another object is to provide means for adjusting certain parts of the machine for labeling rolls of different diameter. 65

Other objects and uses relating to specific parts of the machine will be brought out in the following description.

In the drawings:

Figure 1 is a top plan of a labeling machine embodying the various features of my invention.

Figure 2 is an enlarged transverse vertical sectional view taken in the plane of 75 line 2—2, Figure 1. Enlarged.

Figures 3 and 4 are longitudinal sectional views taken respectively in the planes of lines 3—3 and 4—4, Figure 5.

Figure 5 is a horizontal sectional view 80 taken in the plane of line 5—5, Figure 3, the central portion of the machine being broken away.

Figures 6 is a horizontal sectional view taken in the plane of line 6—6, Figure 2. 85

Figures 7 and 8 are enlarged detail vertical sectional views taken respectively in the plane of lines 7—7 and 8—8, Figure 1.

Figure 9 is a further enlarged detail vertical sectional view taken in the plane of line 90 9—9, Figure 7.

Figures 10 and 11 are detail sectional views taken respectively in the planes of lines 10—10 and 11—11, Figure 9.

Figure 12 is a detail vertical sectional view 95 taken in the plane of line 12—12, Figure 8.

Figure 13 is a detail transverse vertical sectional view taken in the plane of line 13—13, Figure 2.

Figures 14, 15, 16, 17 and 18 are enlarged 100

detail vertical sectional views taken respectively in the planes of lines 14—14, 15—15, 16—16, 17—17 and 18—18, Figure 5.

Figure 19 is an enlarged detail sectional view of the bearing for one end of one of the mandrels and adjacent portion of the guide for said bearing taken in the plane of line 19—19, Figure 4, the end of the mandrel being shown by dotted lines.

Figure 20 is an enlarged sectional view of the bearing for the other end of the same mandrel and adjacent portion of the guide therefor taken in the plane of line 20—20, Figure 2.

Figure 21 is a diagrammatic view of the motor circuit and controlling switches therefor.

Figure 22 is a detail sectional view taken in the plane of line 22—22, Figure 5.

Figure 23 is a detail sectional view taken in the plane of line 23—23, Figure 22.

Figure 24 is an enlarged detail sectional view taken in the plane of line 24—24, Figure 2.

Figure 25 is a detail sectional view partly broken away, taken in the plane of line 25—25, Figure 2.

Main supporting frame

As illustrated the main supporting frame is substantially rectangular and comprises a pair of similar longitudinally extending upright sections —1— arranged in transversely spaced parallel relation and connected near their ends by transverse tie rods —2— which are surrounded by tubular spacing sleeves —3— abutting against the inner faces of the sections —1— to hold the latter in spaced parallel relation as shown more clearly in Figures 1 to 6 inclusive and Figure 13, the frame sections —1— being provided with bosses —3'— adapted to enter the adjacent ends of the spacing sleeves —3— to hold the latter against lateral displacement as shown more clearly in Figure 6.

Two of these tie rods —2— and their spacing sleeves —3— are located near the lower corners of the frame sections —1— while the other tie rod —2— and its spacing sleeve —3— is located near the upper front corner of the frame sections as shown more clearly in Figures 2, 3, 4 and 6.

A brace bar —2'— extends across the intervening space between the rear ends of the frame sections —1— and is bolted or otherwise secured to said sections as shown more clearly in Figure 6 and serves to receive and support a pair of brackets —4— which are bolted or otherwise secured to the brace bar —2'— to extend upwardly therefrom for receiving and supporting a horizontal delivery table or shelf —5— as shown more clearly in Figures 1, 2 and 5.

This delivery table or shelf —5— is arranged at the rear end of the machine to

form a support upon which the mandrels with the labeled rolls thereon may be temporarily supported immediately following the labeling operation.

The upper edges of the frame sections —1— are disposed in substantially the same horizontal plane for receiving and supporting a pair of longitudinally extending guide plates —6— and pendent legs —7— near the ends thereof bolted or otherwise secured to the upper faces of the frame sections —1— as shown more clearly in Figures 14 and 15 for supporting the guide plates in transversely spaced parallel relation, the legs —7— for each guide plate being arranged in longitudinally spaced relation for a purpose hereinafter described.

These guide plates —6— extend practically the entire length of the frame sections —1— in a plane some distance above the upper faces of said sections and are provided in their inner sides with lengthwise grooves —6'— extending from end to end thereof for receiving and guiding the mandrel bearings on the conveyor presently described.

Mandrel conveyor mechanism

A rotary power-driven cross shaft —8— is journaled in suitable bearings —9— on the rear ends of the guide plates —6— as shown more clearly in Figure 5 to extend transversely beneath the delivery table —5— and is provided near the bearings —9— with a pair of sprocket wheels —10— for receiving and supporting the adjacent portions of a pair of link-belts —11—.

These belts extend forwardly along corresponding sides of the machine and are mounted at their forward ends upon and around upper and lower pairs of sprocket wheels —12— and —12'—, the upper set of sprocket wheels —12— being journaled upon relatively short stub-shaft bearings —13— on the front ends of the side plates —6— as shown more clearly in Figure 5.

The lower set of sprocket wheels —12'— are journaled upon relatively short stub-shaft bearings —14— on the front portions of the frame —1— as shown in Figures 3 and 4.

The upper portions of the peripheries of the sprocket wheels —8— and —10— are disposed in substantially the same horizontal plane as the lower walls of the adjacent guide groove —6'— of the guide plates —6— so that the intermediate portion of the link belt —11— may ride along and upon said lower wall as shown more clearly in Figure 3 while the lower side of the chains sag more or less between the lower peripheral portions of the sprocket wheels —8— and lower set of sprocket wheels —12'—.

It is now clear that the upper sides of the link-belts travel in a horizontal plane along and upon the underlying wall or flange of

the guide plates —6— for moving the mandrels carrying the paper rolls along the same plane in a manner presently described.

The upper sides of the link-belts extend horizontally practically the entire length of the machine, one of said belts being provided with a plurality of, in this instance three, bearing blocks —15— secured thereto in uniformly spaced relation longitudinally and adapted to slide along the corresponding guide plate —6— as the conveyor is moved in the direction indicated by arrows in Figures 3 and 4.

Journalized in each of the blocks —15— is a rotary member —16— having a square socket —17— open at its inner end for receiving the adjacent square end of the roll supporting mandrel presently described. See Figure 19.

The other link belt is provided with a corresponding number of bearing blocks —15'— in transverse alignment with the blocks —15— and adapted to slide within and upon the adjacent guide plate —6—, each of the blocks —15'— being provided with a socket —17'— open at the top to receive the adjacent ends of the mandrels and to allow the latter to turn in their respective blocks during the labeling operation.

It is now evident that each bearing block —15— and its companion block —15'— is adapted to receive and support one of the loaded mandrels during the labeling operation and that the object of the open sided sockets —17'— is to facilitate the placing and removing of the loading mandrels upon and from the blocks —15— and —15'— just preceding and succeeding the labeling operation.

Conveyor driving means

An electric motor —M— is mounted upon a bracket —18— on one of the upright sections —1— with its armature shaft —m— extending lengthwise thereof and provided with a worm —19— meshing with a worm-gear —20— which, together with the worm —19—, is mounted within a suitable gear case —18'— on the adjacent upright section —1— of the main supporting frame as shown more clearly in Figure 23.

That is, the gear case —18'— is bolted or otherwise secured to the adjacent upright portion of the near section —1— of the main supporting frame and is provided with suitable bearings for the motor shaft —m— and the supporting shaft as —21— for the gear —20—.

A pulley —22— is secured to the inner end of the gear shaft —21— and is connected by a belt —23— to a relatively larger pulley —24— on the corresponding end of the rear cross shaft —8— carrying the conveyor sprockets —11— as shown more clearly in Figures 4, 5 and 22, the belt being tightened upon its supporting pulleys —22— and

—24— by means of a belt-tightener —25—, as shown in Figures 4, 5 and 22.

It will be noted that the driving connections between the motor —M— and conveyor shaft —8— are arranged to drive the conveyor belts at relatively low rate of speed for effecting a corresponding slow movement of the loaded mandrels along and upon the guide plates —6— during the labeling operations, it being understood that three of these labeling operations occur during each cycle of movement of the conveyor belts —11— by reason of the fact that the conveyor belt is provided with three sets of the bearing blocks —15— and —15'— in uniformly spaced relation upon the conveyor belts for receiving a corresponding number of the loaded mandrels.

As shown by dotted lines in Figure 1 a multiplicity of, in this instance eighteen, toilet paper rolls —u— are provided with the usual tubular pasteboard cores which, together with the rolls, are mounted end to end upon a mandrel —b— having one end square and adapted to be inserted into the corresponding socket —17— of one of the bearing members —15— and its other end placed in the socket —17'— of the companion bearing block —15'—.

This loaded mandrel with the unlabeled rolls thereon is placed in the corresponding set of bearing members —15— and —15'— while the conveyor is at rest with one set of bearing blocks at the front end of the machine and the nearest preceding set of bearing blocks at the rear of the machine, the third set being then on the underlying side of the chain belts from which the mandrel carrying the previously labeled rolls has been removed to permit said bearings to receive another loaded mandrel when brought to the front end of the machine by further movement of the conveyor.

A self-closing electric switch —s—, Figure 21, is connected in the motor circuit and is normally closed to cause the operation of the motor and conveyor mechanism for feeding the loaded mandrels from front to rear of the machine during which the labels are automatically applied to the rolls in a manner hereinafter described but immediately following the labeling operation for each loaded mandrel the switch —s— will be automatically opened by the engagement of one of the switch blocks as —15— with a switch-operating member as —26—, shown diagrammatically in Figure 21 and in full in Figure 4.

That is, the switch member —26— is pivotally mounted upon a switch box —S— on the rear end of one of the guide plates —6— as shown in Figure 4 to normally project into the path of movement of the blocks —15— on the corresponding side of the machine to be engaged by each block for breaking the motor circuit and thereby stopping the motor

and conveyor driven thereby immediately following the labeling operation.

A switch box —S'— is mounted in the top of the front lefthand side of the frame of the machine as shown in Figures 1 and 2, and contains a self-opening starter switch —S'— which is connected in the motor circuit (Figure 21) and is adapted to be closed by a push button —S''— (Figures 1 and 2) for starting the motor after it has been automatically stopped by the opening of the switch —26—.

That is, while the conveyor is at rest with one of the mandrels carrying its load of labeled rolls at the rear end of the machine, another mandrel with its unlabeled rolls is placed in the bearings —15— and —15'— at the front of the machine. The switch —S'— is then temporarily closed by the depression of the push button —S''— to start the motor and conveyor until the switch —S— is allowed to close by the shifting of the adjacent member —15— at which time the switch —S'— may be released and allowed to open with the assurance that the motor and conveyor will continue to feed the second named mandrel and its rolls from front to rear of the machine for labeling the rolls or until the switch —S— is again opened by the corresponding member —15— of the conveyor, this operation being repeated for each loaded mandrel.

Supplemental frame

Each of the upright frame sections —1— is provided intermediate its ends with a pair of similar upright guide posts —27— bolted or otherwise secured thereto in longitudinally spaced relation to project inwardly therefrom as shown more clearly in Figures 3, 4 and 6 and having their inner sides provided with vertical T-shaped slots —28— for receiving and guiding a vertically movable supplemental frame upon which the parts of the label holders are guided in a manner presently described.

This supplemental frame comprises a pair of similar upright plate sections —29— extending lengthwise of the machine in transversely spaced parallel relation adjacent the inner faces of the upright guide bars —27— as shown more clearly in Figures 2, 5 and 6, each plate section —29— being provided with a pair of outwardly projecting T-shaped ribs —30— complementary to and engaged in the corresponding guide grooves —28— for holding the plates in spaced parallel relation and guiding them in their vertical movement.

Suitable means is provided for raising and lowering the side plates —29— of the supplemental frame with the various mechanisms thereon to compensate for varying diameters of the paper rolls to be labeled and for this purpose the plates —29— are provided with vertical threaded apertures —31— adapted to

be engaged by right and lefthand screw shafts —32— and —32'— respectively having their lower ends journaled in suitable brackets —33— on the lower lengthwise bars of the main supporting frame —1— as shown more clearly in Figure 13.

The lower ends of these upright screw shafts —32— and —32'— are provided with beveled gears —34— meshing with companion gears —35— on a cross shaft —36— which is journaled in suitable bearings in the brackets —33— and is provided at one end with a hand wheel —37— by which it may be turned for transmitting rotary motion to both of the upright shafts through the medium of the companion gears. See Figure 13.

Label carrier

The portions of the upright side plates —29— of the supplemental frame between the cross shaft —36— and guide bars —27— are provided in their inner faces with vertical T-shaped slots —38— for receiving complementary vertical ribs —39— on the pendant extensions —40— of a horizontally extending U-shaped frame —41— which forms a part of the label carrier and is arranged with its cross bar facing rearwardly and its opposite arms extending forwardly as shown more clearly in Figure 5, said forwardly extending arms being connected by additional cross bars —42— in longitudinally spaced relation from each other and from the rear cross bar. See Figs. 6 and 25.

The upper faces of the cross bars of the U-shaped frame —41— are disposed in substantially the same horizontal plane for receiving and supporting a multiplicity of label supporting tables —42'— corresponding to the number of rolls to be labeled on each loaded mandrel. See Figures 2, 5, 7 and 8.

The pendant arms —40— are arranged in transversely spaced parallel relation near the inner faces of the opposite side plates —29— as shown in Figure 6 and are provided with vertical threaded apertures —43— adapted to be engaged by separate screw shafts —44— and —44'— having right and lefthand threads respectively for effecting simultaneous vertical movement of the carrier frame —41— in one and the same direction independently of the side plates —29— for bringing the uppermost labels into position to be engaged by the rolls —a— on the mandrel —b—.

The lower ends of the shafts —44— and —44'— are journaled in suitable brackets —45— which are bolted or otherwise secured to the lower lengthwise bars of the main supporting frame which is shown more clearly in Figures 4 and 23 and are provided with beveled gears —46— meshing with companion gears —46'— on an underlying cross shaft —47—, the latter being also journaled

- in suitable bearings in the brackets —45— as shown more clearly in Figure 25.
- One end of the shaft —47— is provided with a hand wheel —48— by which it may be rotated to effect a corresponding rotation of the screw shafts —44— and —44'— and resultant vertical movement of the label supporting frame —41— along the upright guide grooves —38— in the side plates —29— for adjusting the label support with the labels thereon toward and from the path of movement of the mandrels carrying the rolls to be labeled, this adjustment being independent of the vertical adjustment of the side plates —29— along the guide bars —27— for feeding the labels to the rolls as they are successively wrapped around the rolls.
- An additional U-shaped member —41'— similar to the member —41— is mounted upon the opposite arms of said member —41— for lengthwise sliding movement and for this purpose the opposite arms of the member —41— are provided with lengthwise slots —41"— for receiving guide bolts or studs —41'”— on the opposite adjacent arms of the member —41'— the object of which is to permit the label supporting table to be lengthened or shortened according to the lengths of the labels. See Figure 2.
- The bars —41— and —41'— extend continuously transversely of the machine between the side plates —29— for receiving and supporting a multiplicity of label supporting tables —42— corresponding to the number of rolls carried by each mandrel, each table being composed of relatively thin sheet metal sections —42"— and —42'”—, one set of which, as —42"—, is secured to the U-shaped member —41— while the other set as —42'”— is secured to the U-shaped member —41'—, which, together with the plates —42'”—, are adjustable endwise to vary the length of the table according to the length of the labels supported thereon as may be required for rolls of different diameters. See Figures 1, 2 and 5.
- The label supporting tables or tablets —42— are of about the width of the individual stacks of labels which they are adapted to support and are of slightly less width than the rolls upon which the labels are adapted to be wound so that the meeting edges of the several tablets are slightly separated to receive between them guide members for holding the labels against lateral displacement during the rolling operation of the mandrels with the rolls thereon along and upon the uppermost label in a manner hereinafter described.
- The portions of the side plates —29— in front of the vertical shafts —32— and —32'— are provided on their inner faces with lengthwise guide grooves —49— of T-shaped cross section for receiving complementary portions of a pair of longitudinally adjustable slide

plates —50— having lengthwise threaded openings —51— for receiving separate screw shafts —52— as shown more clearly in Figures 6, 14 and 15.

The front ends of these shafts are journaled in suitable bearings —53— on the adjacent ends of the side plates —29— and are provided with hand wheels —54— by which they may be turned for adjusting the slides —50— along the guideways —49— for a purpose presently described. See Figures 5, 6, 14 and 15.

Suitable means is provided for engaging the opposite ends of the labels to assist in guiding them in their vertical movement with the corresponding movement of the tables —42'— and also for holding said labels against endwise displacement during the labeling operations and for this purpose a pair of vertically disposed abutment plates —55— and —55'— are mounted respectively upon the vertically movable side plates —29— and the horizontally movable slides —50— at opposite ends of the label supporting tables —42'— as shown more clearly in Figure 2.

These abutments extend some distance above and below the horizontal plane of the tables —42'— and also laterally beyond said tables in parallel relation a distance apart and are supported endwise independent of the tables so that the latter with or without the labels thereon are free to move vertically between the end abutments.

The opposite ends of the rear end abutment —55— are secured to the inner faces of the upright side plates —29— by angle irons —56—, Figure 5, while the opposite ends of the front abutment —55'— are secured by similar angle irons —56'— to the inner faces of the adjacent slides —50— to move horizontally therewith, it being understood that both of the end abutments may be adjusted vertically with the side plates —29— as the latter are adjusted through the medium of the screw shafts —32— previously described. See Figures 14 and 15.

While the slides —50— are adjusted horizontally through the medium of the screw shafts —52—, the U-shaped bar —41'— carrying the table sections —42'”— will be adjusted by hand, these adjustments being made necessary to accommodate labels of different lengths.

The side plates —29— are connected near their front ends by a tie rod —29'— having its opposite ends seated in suitable sockets in the side plates and held against turning movement by pins —29'— as shown more clearly in Figure 6.

A plurality of upright guide fingers —57— are secured at their lower ends to the tie rod —29'— to extend upwardly therefrom through the spaces between and above the label supporting tablets —42'—, said tie-rod being provided with similar guide fingers ex-

tending across the outer edges of the outermost label supporting tablets as shown in Figures 1, 5 and 6.

The slides —50— are provided with downwardly and rearwardly projecting extensions —58— which are connected by tie rods —29''— similar to the tie rod —29'— for receiving a plurality of upwardly projecting guide fingers —57— similar to the fingers —57— in that they project upwardly through the spaces between and along the outer edges of the outermost label supporting plates —42'— as shown more clearly in Figures 1, 2 and 5.

Suitable means is provided for holding the intermediate portions of the end abutments —55— and —55'— and tie rods —29'— and —29''— against lateral vibratory movement, said means consisting in this instance of a pair of upright bars —59— and —59'— clamped to the lower opposite-end spacing sleeves —3— substantially midway between the opposite upright side sections —1—, Figure 2, for receiving a pair of inverted L-shaped members —60— and —60'—, the upright portion of the member —60— being provided with vertical slots —61— for receiving clamping bolts —62— which are engaged in threaded apertures in the upright members —59—, Figure 2.

The horizontal upper portion of the member —60— is clamped to the intermediate portion of the tie rod —29'— to hold the latter against vibration, said horizontal portion being provided with an upwardly projecting extension —63— which is bolted or otherwise secured to the rear face of the adjacent end abutment —55— as shown in Figure 2, thereby holding the intermediate portion of the abutment against vibration.

The object of the slot and bolt connections between the upright portion of the members —59— and —60— is to permit vertical adjustment of the upper member —60— with the side plates —29— to which the tie rod —29'— is secured.

The upright portion of the L-shaped member —60'— is provided with slots —64— for receiving clamping bolts —64'— which are engaged in threaded apertures in the member —59'— to permit vertical adjustment of the members —60'— with the side plates —29— which carry the slides —50—.

The upper horizontal portion of the member —60'— is provided with a slot —65— for receiving clamping bolts —65'— which are engaged in threaded apertures in the lower end of an upwardly projecting bracket —66— to which the front end abutment —55'— is bolted or otherwise secured, the member —66— having its rear end clamped to the adjacent tie rod —29''— for holding the latter against vibration and also performing a similar function for the intermediate portion of the abutment —55'—. See Figure 2.

Owing to the fact that the front end abutment —55'— is secured to the slides —50— and that the member —66— is secured to the intermediate portion of the front end abutment and to the tie rod —29''— said member —66— becomes indirectly a part of the slides —50— in that it is adapted to be adjusted horizontally with said slide by reason of the slot and bolt connections —65— and —65'— between the members —60'— and —66—, see Figure 2.

The opposite lengthwise guide bars —6— for the mandrel bearings —15— and —15'— on the link belts —11— are provided with downwardly projecting lengthwise extensions —67— and —67'— supported by the legs —7— to form lengthwise guides for a pair of similar brackets —68— and —68'— which are adjustable along and upon their respective connections —67— and —67'— and are adapted to be held in their adjusted positions by clamping bolts —69— shown more clearly in Figures 14 and 15.

That is, the extensions —67— and —67'— are provided with lengthwise slots —70— of T-shaped cross section for receiving complementary heads of the bolts —69— which in turn are engaged in apertures in the outer walls of the brackets —68— and —68'— respectively, Figures 5, 14 and 15, to permit lengthwise adjustment of the brackets along their respective guides —67— with the plates —50—.

The inner portions of these brackets —68— and —68'— are operatively connected to their respective slides —50— and —50'— to move therewith lengthwise of the machine when adjusted by means of their respective screw shafts —52—, Figures 14 and 15.

The brackets —68— and —68'— are provided with vertical guide ribs —71— which are T-shaped in cross section for engagement in complementary slots —72— in the adjacent portions of the corresponding slides —50— as shown in Figures 5, 14 and 15.

The object of these sliding connections between the brackets —68— and —68'— and the corresponding slides —50— on the vertically movable side plates —29— is to permit vertical adjustment of those plates by their respective screw shafts —44— and —44'—, Figure 25, as previously described, it being understood that the brackets —68— and —68'— are held against vertical movement by reason of their connections with the stationary guide members —67— and —67'— while at the same time they may be moved lengthwise of the machine along the slots —49— and —70— when adjusting the slides —50— through the medium of their respective screw shafts —52—.

An approximately equal number of inverted labels as —c—, Figures 7, 8 and 10, are

stacked flatwise one upon the other upon the several platforms or tables —42'— with their ends closely adjacent the rear and front abutments —55— and —55'— which, together with the platforms —42'—, have been previously adjusted to correspond to the lengths of the labels, it being understood that the label support with the labels thereon will also be adjusted vertically to bring the uppermost label into contact with the underside of the rolls on the mandrels as the latter are fed horizontally along the guide bars —6— and that the side plates —29— will also have been previously adjusted vertically to conform to the particular diameter of the rolls to be labeled.

Label pasting mechanism

Suitable means is provided for automatically applying paste to the upper surfaces of the front and rear ends of the uppermost labels of the several stacks so that as each mandrel with the unlabeled rolls thereon is rolled from its starting position along the upper surfaces of the labels the rolls will adhesively pick up the pasted front ends of the labels and wrap the latter around the peripheries thereof until the rear pasted ends of the labels are brought into overlapping relation with and adhesively secured to the outer surfaces of the previously pasted front ends, it being understood that the lengths of the labels will be somewhat greater than the circumference of the rolls to permit said overlapping relation.

The first paste-applying means comprises a horizontal paste-containing trough —T— mounted upon and between the side plates —50— to extend entirely across the front ends of the label holders —42'— for longitudinal adjustment with said plates and also for vertical adjustment with the supplemental frame sections —29— as shown in Figures 1, 2, 5 and 7.

A pair of parallel rocker-shafts —73— and —74— are journaled in suitable bearings in the side plates —50— and intermediate bracket —66— to extend the entire length of the trough —T— near the upper rear edge thereof as shown in Figures 1, 2, 5 and 7, the shaft —73— being provided with a plurality of crank-arms —73'— carrying at their outer ends a rod or wire —73"— which is movable with the shafts —73— into and out of the paste in the container —T— for transferring the paste to a plurality of wipers on the shaft —74— for re-transfer to the front ends of the labels in a manner presently described. See Figures 2, 5 and 7.

The shaft —74— is arranged in a plane above and at the rear of the shaft —73— and is provided with a series of crank arms —74'— carrying at their outer ends a corresponding number of wipers —74"—, one for each stack of labels —c—, having convex out-

er faces normally lying in the path of movement of the wire —73"— to permit the paste to be spread thereon by the wire as the latter is moved across the same, said wipers being arranged to apply the paste thereon to the central portions of the upper faces of the front ends of their respective labels immediately following the application of the paste thereto by the wire —73"—. See Figures 2, 5 and 7.

The shaft —73— is normally in position to hold the wire —73"— in the paste in the container —T— and is adapted to be rocked from its normal position at each movement of the conveyor with a loaded mandrel thereon and for this purpose a cam-lever —75— is pivoted at —75'— to the bracket —68— to extend rearwardly from its pivot with its cam —75"— in the path of the conveyor blocks —15'— so that the rearward movement of each block with the loaded mandrel therein will engage and depress the cam lever —75—. See Figures 2, 3 and 5.

The rear end of the cam lever —75— is connected by a link —76— to a crank arm —76'— of a stub shaft —77— which is journaled in the bracket —68— and is provided with a forwardly projecting crank-arm —77'— connected by a link —78— to one of the arms of a bell crank lever —79— pivoted at —79'— to the bracket —50— and having its other arm provided with a toothed segment —79"— meshing with a gear —80— on the wire supporting shaft —73— so that each depression of the cam lever —75— will cause the wire —73"— to move from its normal position in the paste-container into engagement with the convex surfaces of all of the wipers —74"— for spreading the paste thereon after which the wire and its operating means including the cam lever —75— will be returned to their normal positions by a retracting spring —81—, shown in Figures 2 and 16.

Immediately following the return of the wire —73"— to its normal position, after applying its paste to the wipers —74"—, the shaft —74— carrying the previously pasted wipers —74"— will be rocked from its normal position to cause said wipers to apply the paste to the uppermost label and for this purpose a relatively short rock-shaft —82— is journaled on the right-hand side-plate —68'— near the front end of the machine and is provided on its outer end with a cam-crank —83— having its cam-face —83'— normally disposed in the path of the corresponding bearing blocks —15— to be depressed thereby as the loaded mandrel therein is moved rearwardly from its starting position. See Figures 1, 4, 5 and 18.

The inner end of the stub-shaft —82— is provided with a crank-arm —82'— connected by a link —82"— to a toothed segment —84— which is pivoted at —84'— to the ad-

jacent plate —68— to swing downwardly against the action of a spring —84— and meshes with a pinion —84— on a cross-shaft —85— for rocking said shaft as the cam-crank —83— is depressed, said cross-shaft being journaled in the opposite side plates —50—. See Figures 5 and 18.

This shaft —85— is provided with a multiplicity of tight gears —85—, one for each of the wipers —74—, meshing with a corresponding number of companion gears —85— which are loosely mounted on the wiper shaft —74— and are provided with reduced axially extending hubs —85— upon which the hubs of the wiper-arms —74— are journaled for limited relative angular movement. See Figures 1, 2, 5, 7 and 9.

The gears —85— are held against axial movement by collars —86— which are secured by set screws or other fastening means to the shaft —74— while the hubs of the several wiper arms —74— are held against axial movement between their respective gears —85— and collars —86— which are secured by set screws or other fastening means to the hubs —85— of their respective gears for angular movement with said gears. See Figures 9 and 11.

Each collar —86— is provided with an end lug —87— projecting into a circumferentially elongated slot —87— in the hub of the adjacent wiper arm —74— for engaging one end of a coil spring —87— which forms a yielding connection between the wiper arm and collar —86— and enables the wipers —74— to engage the labels with a yielding pressure to compensate for slight variations in the height of the labels as shown more clearly in Figures 9 and 11 and also causes a slight sliding movement of the wipers upon their respective labels to irregular spreading of the paste when the rolls are brought into contact therewith.

It is now clear that the entire series of wipers —74— are rocked from their paste-receiving positions to their paste-applying positions and return at each depression and return of the cam —83— and independently of the shaft —74— thus completing the initial pasting operation.

Label-gripping

Suitable means is provided for holding the uppermost labels against displacement during the pasting operation just described and also for releasing said labels when adhesively picked up by the advancing rolls —a— and for this purpose the shaft —74— is provided with a series of pairs of gripper-supporting hubs —88— (one pair for each stack of labels) secured thereto by set-screws —88— or equivalent fastening means to rock therewith, each hub being provided with a tangentially extending gripper arm —89— pivoted thereto at —89— for vertical rocking

movement and yieldingly urged forwardly and downwardly by a spring —89— as shown more clearly in Figures 9 and 10 to engage the uppermost label with a yielding pressure and thereby to compensate for slight variations in the height of the corresponding stack of labels.

The label-engaging faces of the grippers —89— are preferably serrated to reduce the liability of slippage thereof on the labels.

Suitable means is provided for automatically operating the rock-shaft —74— and grippers —89— thereon relatively to the loose gears —85— and for this purpose a cam lever —90— is secured to a pivoted stud —90— on the carriage —68— at the left hand side of the machine just at the rear of the cam lever —75— as shown in Figures 1, 2, 3, 5 and 17, the pivotal stud —90— being provided with a crank-arm —90— which, in turn is connected by a link —90— to a toothed segment —91—, the latter being pivoted at —91— and meshing with a tight gear —91— on the shaft —74— as shown more clearly in Figure 17.

The cam lever —90— is yieldingly held in its up position in the path of movement of the mandrel-supporting bearings —15— by a spring —91—, Figure 3, thereby normally holding the grippers —89— in engagement with the labels, said cam lever being adapted to be depressed to withdraw the gripping members from the labels at about the same time that the wipers —74— are withdrawn from their paste-applying positions to allow the rolls —a— on the mandrel to have free contact with the previously pasted portions of the labels without interference with the wipers or grippers.

As soon as the uppermost labels have been adhesively picked up by the rolls and while the latter are rolling the labels thereon, the shaft —74— and grippers —89— are returned to their gripping positions by the retracting spring —91— for the cam lever —90— thus completing the initial label-pasting and gripping operations.

It will be noted, however, that each wiper —74— is located between each pair of grippers —89— so as to make a single initial application of the paste to each label substantially midway between the grippers and opposite longitudinal edges of the labels.

Rear end pasting

A cam-lever —92— is pivoted at —92— to the right hand side —6— of the frame to project into the path of the corresponding mandrel bearings —15— some distance to the rear of the cam lever —83— (Figures 4 and 5) to be depressed thereby as the loaded mandrel is moved rearwardly, said cam-lever —92— being connected by a link —92— to a crank arm —92— on the adjacent end of a rock-shaft —93— which is journaled in the

rear ends of the opposite lengthwise members —29— to rock about its axis as the cam lever —92— is depressed. See Figures 2, 4, 5 and 7. This rock-shaft —93— extends along the upper rear edge of a paste containing receptacle —T'— and is provided with crank-arms —93'— carrying a wire —93''— which is movable into and out of the paste in said receptacle for transferring the paste to a series of wipers by which the paste is applied to the rear ends of the uppermost labels in a manner presently described, said cam-lever —92— and parts actuated thereby being returned to their normal positon by a spring —93'''—, Figure 2.

15 The paste containing receptacle —T'— is secured to and between the members —29— just at the rear of the label holder as shown in Figures 2, 4, 5 and 7.

20 A cam-lever —94— (Figures 2, 3 and 5) is pivoted at —94'— to the left hand side of the frame —1— to project into the path of the mandrel-bearings —15— some distance to the rear of the cam-lever —90— and is connected by a link —94''— to a toothed segment —95— which is pivoted at —95'— to the adjacent frame member —1— and meshes with a tight gear —95''— on a rock-shaft —96— for rocking said shaft in one direction against the action of a retracting spring —95'''— shown in Figure 3.

25 The rock-shaft —96— is journaled in the opposite side members —29— and is provided with a series of pairs of crank-arms —96'—, one pair for each stack of labels —c—, and each crank-arm is provided with a convex wiper —96''— in the path of the rod or wire —93''— to receive paste therefrom as the wire is rocked upwardly and rearwardly from its normal position by the 30 rock shaft —93— in the manner previously explained, said wipers being arranged to apply the paste thereon to the upper surfaces of the rear ends of the uppermost labels at 35 opposite sides of the longitudinal centers thereof as the shaft —96— is rocked by the depression of the cam lever —94— as shown by dotted lines in Figure 8.

40 Each crank-arm —96'— is preferably composed of sections, one of which is adjustably secured to the rock-shaft —96— while the other section carrying the wiper —96''— is yieldingly connected to the first named section by a spring —96'''— as shown in Figures 8 and 12 to cause the wipers to engage the labels with a sliding contact for spreading the paste in thin layers thereon.

Rear grippers

45 Suitable means is provided for holding the rear ends of the uppermost labels against displacement while the labels are being wrapped upon the rolls by the rolling motion of the rolls —a— thereon and while the 50 paste is being applied thereto, and also for

releasing the labels after the wrapping and pasting operations are completed and for this purpose a rock-shaft —97— is journaled in the opposite side members —29— and provided with a series of hubs —97'— having 55 gripper arms —97''— similar to the front hubs —88— and gripper arms —89— except that there is only one hub —97'— and one gripper arm —97''— for each stack of labels and that each hub and gripper arm is arranged midway between the corresponding pair of wiper arms —96— to engage the corresponding central portion of the uppermost label.

60 That is, each hub —97'— is secured to the shaft —97— while each gripper-arm —97''— is pivotally and yieldingly mounted on its corresponding hub in substantially the same manner as the front end grippers shown in Figure 10.

65 A cam-lever —98— is pivoted at —98'— to the right hand side member —67'— (Figures 4 and 5) near the rear end of the machine to project upwardly into the path of the mandrel bearings —15— to be engaged and depressed thereby as the loaded mandrel continues its rearward movement, said cam-lever being connected by a link —98''— to a toothed segment —99— which, in turn, is pivoted at —99'— to the side member —67— 70 and meshes with a tight gear —99''— on the gripper shaft —97— for rocking said shaft and grippers —97''— thereon upwardly and rearwardly for releasing the labels just preceding the completion of the wrapping operation and pasting of the rear end of the labels over and upon the previously pasted front 75 ends of the same labels to the rolls as previously explained, thus completing one labeling operation.

80 As soon as the cam-lever —98— is released by the passing of its operating member —15— it, together with the segment —99— and parts actuated thereby, is returned to its normal gripping position by a retracting spring —98'''—, Figure 4.

Label table feed

85 Suitable means is provided for automatically intermittently feeding the label-supporting carriage upwardly a distance equal to the thickness of a label immediately following the removal of the uppermost labels caused by the wrapping of said labels around and upon their respective rolls —a— and for 90 this purpose a lever —100— is secured to a rock-shaft —100'— at the rear end of the frame —1— and projects upwardly therefrom into the path of mandrel bearings —15'— to be thereby rocked rearwardly and 95 downwardly as the loaded mandrel continues its rearward movement. See Figures 2, 3, 5 and 6.

100 The rock-shaft —100'— is provided a crank-arm —100''— connected by a link 105

—101— to a rock-arm —101'— which is loosely pivoted on the cross-shaft —47— as shown in Figures 1, 2, 3, 4 and 6 and is provided with a pivoted pawl —101"— for engaging the teeth of a ratchet wheel —102— tight on the shaft —47— to rotate said shaft and thereby cause slight angular movement of the upright screw shafts —44— and corresponding upward movement of the label-supporting carriage —40— at each rearward movement of the rock-arm —100—, the operating mechanism for the carriage being arranged to raise the carriage upwardly a distance equal to the thickness of the label at each cycle.

The continued rearward movement of the loaded mandrel with the labeled rolls thereon causes the conveyor block —15'— to release the cam lever —100— and allowed the latter, together with the parts operated thereby, to be returned to its normal position by means of a spring —103— shown in Figure 3.

At about the same time that the lever —100— is rocked rearwardly by the rearward movement of the upper side of the conveyor block —15'— the opposite conveyor block —15— will engage and operate the switch member —26—, Figure 21, to open the switch —s— and thereby stop the motor —M— and conveyor —11— driven thereby, thus leaving the mandrel with the labeled rolls thereon directly over and upon the delivery table —5— until the switch —s'— is again closed by hand to start another cycle of operation of the motor.

While the loaded mandrel with the labeled rolls thereon is resting upon the table —5— the mandrel may be removed from its bearing —15— and —15'— and withdrawn endwise from the labeled rolls leaving the latter to be displaced rearwardly from the table for drying the paste thereon until displaced by the next succeeding series of labeled rolls.

When the mandrel is removed from the labeled rolls it is taken to the paper-roll cutting machine to be reused for receiving another set of rolls to be labeled, it being understood that the present machine will be installed in close proximity to said cutting machine for convenience of transfer of the mandrels from one machine to the other.

Operation

When the machine is at rest one set of conveyor blocks will be disposed at the front end of the machine and another set at the rear end of the machine, at which time both of the motor-controlling switches —s— and —s'— will be opened.

One of the mandrels with a series of rolls to be labeled thereon is then placed by hand in the conveyor blocks in the front of the machine after which the switch —s'— will be closed by hand, thereby starting the motor and conveyor belt driven thereby until the

conveyor block —15— at the rear of the machine is moved out of engagement with the switch member —26— thereby allowing the switch —s— to close, the switch —s— being then released to its open position with the assurance that the motor —M— and conveyor belt will continue to operate to cause the rolls on the loaded mandrel to roll along and upon the uppermost labels which have been previously pasted at their front ends in the manner described so that immediately upon the first contact of the rolls with the front ends of the labels the latter will be picked up by the paste thereon and wrapped upon the rolls as they continue their rearward rolling movement.

When the rolls with the labels wrapped thereon approach the rear end of the machine the rear ends of the labels will be pasted in a manner described and adhesively applied to the outer faces of the previously pasted ends of the labels, thus completing the labeling operation of the rolls on that particular mandrel.

Immediately following this labeling operation the rear conveyor blocks carrying the labeled rolls will operate the switch member —26— to open the switch and thereby stop the motor with the rolls resting upon the rear delivery table —5— and at the same time presenting the nearest succeeding set of conveyor blocks to the front end of the machine for receiving another loaded mandrel.

As previously stated, with the rolls are labeled in the manner described and disposed on the table —5— the mandrel is removed and returned to the paper-cutting machine for re-loading leaving the labeled rolls on the table to be displaced by the nearest succeeding set of labeled rolls.

The labeling machine shown and described simultaneously and automatically labels a relatively large number of rolls in one and the same operation, thereby greatly reducing the labor and also greatly increasing the output for a given period of time, but it is evident that various changes may be made in the detail construction and operation of the machine without departing from the spirit of this invention.

What I claim is:

1. In a machine for applying labels to toilet paper rolls, means for supporting a multiplicity of stacks of labels side by side in parallelism with their uppermost labels in substantially the same plane, means for applying paste to both ends of the upper surfaces of the uppermost labels while the latter are lying flatwise in the stack, means for rotatively supporting a corresponding number of toilet paper rolls end to end in alignment with their respective stacks of labels, and means for moving the roll-supporting means along the upper sides of said stacks with the rolls in contact with the pasted surfaces of

- the uppermost labels and thereby to rotate the rolls for wrapping the labels thereon.
2. In a machine for wrapping labels around and upon the peripheries of paper rolls, means for supporting a multiplicity of stacks of labels side by side with their upper faces in about the same plane, means for applying an adhesive to the upper surfaces of the uppermost labels near the ends thereof, and means for simultaneously rolling a corresponding number of rolls along and upon said adhesive surfaces to cause the labels to adhere thereto and to be wrapped thereon, a mandrel for supporting the rolls co-axially thereon, and means for feeding the mandrel with the rolls thereon along the labels.
3. In a machine for wrapping labels around and upon the peripheries of paper rolls, means for supporting a multiplicity of stacks of labels side by side with their upper faces in about the same plane, means for applying an adhesive to the upper surfaces of the uppermost labels near the ends thereof, and means for simultaneously rolling a corresponding number of rolls along and upon said adhesive surfaces to cause the labels to adhere thereto and to be wrapped thereon, a mandrel for supporting the rolls co-axially thereon, an endless conveyor for supporting the mandrel and feeding the same lengthwise of the labels, and means for operating the conveyor.
4. In a machine for wrapping labels around and upon the peripheries of paper rolls, means for supporting a multiplicity of stacks of labels side by side with their upper faces in about the same plane, means for applying an adhesive to the upper surfaces of the uppermost labels near the ends thereof, grippers engaging and holding the uppermost labels during the pasting and wrapping operations, and means for rolling a corresponding number of rolls along and upon said adhesive surfaces to cause the labels to adhere thereto and to be wrapped thereon.
5. In a labeling machine of the character described, means for supporting a multiplicity of labels side by side in about the same plane, means for applying paste to corresponding surfaces of the labels near both ends thereof, means including an endless conveyor for rolling the rolls along and against the pasted surfaces of the rolls, and a track for supporting a portion of the conveyor in a plane substantially parallel with the label supporting means.
6. In a labeling machine of the character described, means for supporting a multiplicity of labels side by side in about the same plane, means for applying paste to corresponding surfaces of the labels near both ends thereof, means including an endless conveyor for rolling the rolls along and against the pasted surfaces of the rolls, and
- a track for supporting a portion of the conveyor in a plane substantially parallel with the label supporting means, an electric motor, means for transmitting motion from the motor to the conveyor, a normally closed electric switch controlling said motor, and means actuated by the conveyor for automatically opening the switch to stop the motor immediately following each labeling operation.
7. In a labeling machine of the character described, means for supporting a multiplicity of labels side by side in about the same plane, means including an endless conveyor for rolling a multiplicity of rolls along and against the labels, and means actuated by the conveyor for applying paste to corresponding faces of the labels near both ends thereof before contact of the rolls therewith to cause the labels to adhere to and to be wound upon the rolls as the latter are moved along the labels.
8. In a labeling machine of the character described, means for supporting a multiplicity of labels side by side in about the same plane, means including an endless conveyor for rolling a multiplicity of rolls along and against the labels, and means actuated by the conveyor for applying paste to corresponding faces of the labels near both ends thereof before contact of the rolls therewith to cause the labels to adhere to and to be wound upon the rolls as the latter are moved along the labels, separate sets of grippers normally engaging the front and rear ends of the labels respectively, means actuated by the conveyor for releasing the front grippers just before the rolls contact with the front ends of the labels, and means actuated by the conveyor for releasing the rear grippers just before the rolls leave the rear ends of the labels.
9. In a labeling machine of the character described, means for supporting a multiplicity of labels side by side in about the same plane, means including an endless conveyor for rolling a multiplicity of rolls along and against the labels, and separate devices actuated in sequence by the conveyor for applying paste to said labels near opposite ends thereof for contact with the rolls to cause the labels to be adhesively wrapped around and upon the rolls as the latter are rolled along and against the labels.
10. The herein described method of labeling paper rolls, consisting in taking the mandrels with a multiplicity of rolls thereon directly from the cutting and winding machine, supporting a multiplicity of stacks of labels in substantially the same plane, applying paste to the uppermost labels of each stack, and rolling the loaded mandrel along said pasted surfaces with the rolls in contact therewith from end to end of the labels to cause the latter to be wrapped upon the rolls.
11. In a machine for wrapping labels

around and upon the peripheries of paper rolls, means for supporting a multiplicity of stacks of labels side by side with their upper faces in about the same plane, means for applying an adhesive to the upper surfaces of the uppermost labels near the ends thereof, and a mandrel movable along and above said labels and supporting a plurality of the rolls co-axially thereon for engaging said adhesive surfaces to cause the labels to adhere thereto and to be wrapped thereon.

12. In a labeling machine of the character described, means for supporting a multiplicity of labels side by side in about the same plane, means for applying paste to corresponding surfaces of the labels near both ends thereof, and means for rolling a corresponding number of rolls along and against the pasted surfaces to cause the labels to adhere to and to be wrapped upon said rolls, said rolling means including an endless conveyor and a mandrel mounted thereon upon which the rolls are co-axially mounted end to end.

13. In a labeling machine of the character described, means for supporting a multiplicity of labels side by side in about the same plane, means for applying paste to corresponding surfaces of the labels near both ends thereof, means for rolling a corresponding number of rolls along and against the pasted surfaces to cause the labels to adhere to and to be wrapped upon said rolls, said rolling means including an endless conveyor having journal bearings, and a mandrel journaled in said bearings and supporting the rolls co-axially thereon.

14. In a labeling machine of the character described, means for supporting a multiplicity of labels side by side in about the same plane, means for applying paste to corresponding surfaces of the labels near both ends thereof, means for rolling a corresponding number of rolls along and against the pasted surfaces to cause the labels to adhere to and to be wrapped upon said rolls, said rolling means including a mandrel mounted upon the conveyor and upon which the rolls are co-axially mounted end to end, and means actuated by said conveyor for feeding the label support toward the path of travel of the rolls as the labels are successively wrapped upon the rolls.

15. In a machine for applying labels to toilet paper rolls, means for supporting a multiplicity of stacks of labels side by side in parallelism with their uppermost labels in substantially the same plane, means for applying paste to the upper faces of the uppermost labels near both ends thereof, means for rolling a corresponding number of substantially coaxial toilet paper rolls along and upon the pasted faces of the labels to cause the latter to be wrapped around their respective rolls during said rolling motion,

and means for lengthening and shortening the label supporting means to correspond to labels of different lengths.

16. In a machine for applying labels to toilet paper rolls, means for supporting a multiplicity of stacks of labels side by side in parallelism with their uppermost labels in substantially the same plane, means for applying paste to the upper faces of the uppermost labels near both ends thereof, means for rolling a corresponding number of substantially coaxial toilet paper rolls along and upon the pasted faces of the labels to cause the latter to be wrapped around their respective rolls during said rolling motion, and means for engaging opposite lengthwise edges of the labels of the several stacks to hold them against contact with each other.

In witness whereof I have hereunto set my hand this 29th day of March, 1930.

JESSE A. BLANN.
